UNITED STATES PATENT OFFICE.

CHARLES L. DAVIS, OF DETROIT, MICHIGAN, ASSIGNOR OF ONE-HALF TO HARRY W. FROST, OF DETROIT, MICHIGAN.

ELECTRIC VAPORIZER.

1,095,557.

Specification of Letters Patent.

Patented May 5, 1914.

Application filed December 22, 1912. Serial No. 739,031.

To all whom it may concern:

Be it known that I, CHARLES L. DAVIS, a citizen of the United States of America, residing at Detroit, in the county of Wayne 5 and State of Michigan, have invented certain new and useful Improvements in Electric Vaporizers, of which the following is a specification, reference being had therein to the accompanying drawings.

10 The invention relates to electric vaporizers more particularly designed for use in connection with carbureters, and the invention consists in the novel construction and arrangement whereby the liquid fuel is heated 15 during its transit to the discharge nozzle.

The invention further consists in the means for generating the heat in the center of the fluid column, whereby the vaporization is effected with the minimum consumption 20 of electrical energy, and further in various features of construction as hereinafter set forth.

In the drawings: Figure 1 is a diagram showing my vaporizer as applied to one type 25 of carbureter. Fig. 2 is a similar view showing a modified construction.

A is a carbureter of any suitable construction, but as shown comprises a double tempered air and vapor mixing tube B; a liquid 30 discharge nozzle C at the center of said tube; and a float chamber D adjacent the tube. The liquid fuel is conveyed from the float chamber to the nozzle through the connecting passage E, from which it rises in the 35 nozzle to an elevation normally slightly below the discharge orifice.

My improved vaporizer is located within the passage leading to the discharge orifice of the nozzle and as shown in Fig. 1, is arranged centrally within the nozzle. The construction of the unit may be of any suitable form, but as shown, consists of a casing a secured into an opening in the under side of the carbureter casing and which projects 45 up axially within the nozzle C and forms a valve stem for controlling the same, leaving between the casing a and the nozzle a sufficient passage for the gasoline or whatever is to be vaporized. The upper end of this casing is closed by a plug, to which is attached the wire b which is the heat-generating resistor. At the lower end this wire is connected in any way with the electric circuit; but I have shown it as provided with a disk-

shaped end c against which the plate d is 55 clamped by suitable screws e.

f is insulation between the head c and the head of the casing a. The screws e are also suitably insulated. The plate d is provided with a screw thread stem g to which the 60 electric conductor h may be connected. The wire b is insulated from the casing except at the upper end by a suitable insulation i.

It will be seen that the gasoline coming 65 from the cup through the passage E will pass upwardly in a thin stream surrounding the vaporizer casing a, and it will be rapidly and highly heated at the point from which it is used, thereby greatly assisting in the vaporization of the gasoline for carbureting air. 70

Instead of having the heating element within the feed nozzle it may be applied to any other passage leading to the nozzle--as, for instance, as shown in Fig. 2, I have shown it applied in a plug in the supply 75 passage E in a slightly different form of carbureter. In this construction the plug G has a counter-bore in the upper end in which a metallic cup h, closed at the upper end by a cap s, is supported, the cup having a neck 80 portion l passing through a smaller opening in the plug and secured thereto by a nut m.

n is a stem passing through the neck l and connected at its upper end to a wire o which is connected to the top of the cup h. The 85 stem is insulated from the cup by a suitable insulation q. h is the wire leading to the battery.

The wire o constitutes the heat-generating resistor, and the gasoline coming from the 90 cup through the passage E will pass in a thin body over the cap s and will be heated in the desired manner by the heat-generator and the heat-insulating element o.

It is obvious that other forms may be employed than the two above disclosed, without departing from the scope of my invention. 95

What I claim as my invention is:

1. A liquid fuel vaporizer comprising a 100 discharge nozzle and an electrical heating unit arranged centrally within the fluid column leading to the discharge orifice of said nozzle, said heating unit being insertible through the lower portion of said nozzle. 105

2. A liquid fuel vaporizer comprising a fluid discharge nozzle, and an electrical heating unit arranged centrally within said

nozzle and secured into an opening in the underside thereof.

3. A liquid fuel vaporizer comprising a fluid discharge nozzle, a valve stem for controlling the same, and an electrical heating unit applied to said valve stem.

4. The combination with a carburetor having an air and vapor mixing tube and a liquid fuel nozzle discharging thereinto, of 10 electrical heating means for heating the fluid

during transit to said nozzle said electrical heating means being insertible into the carburetor as a plug unit.

In testimony whereof I affix my signature in presence of two witnesses.

CHARLES L. DAVIS.
